(57) **CLAIM**

The ornamental design for a toilet for pets, as shown and described.

DESCRIPTION

FIG. 1 is a perspective view of a toilet for pets showing my new design;

FIG. 2 is an enlarged view of the encircled portion of the toilet for pets as designated No. 2 in FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled portion of the toilet for pets as designated No. 9 in FIG. 3;

FIG. 10 is an enlarged view of the encircled portion of the toilet for pets as designated No. 10 in FIG. 3;

FIG. 11 is an enlarged view of the encircled portion of the toilet for pets as designated No. 11 in FIG. 4; and,

FIG. 12 is an enlarged view of the encircled portion of the toilet for pets as designated No. 12 in FIG. 4.

The long-short-long dash lines depict locations of the enlarged portions and form no part of the claimed design.

1 Claim, 10 Drawing Sheets
